UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

ARTICLE-HOLDER.

1,155,562.

Specification of Letters Patent.

Patented Oct. 5, 1915.

Application filed April 10, 1914. Serial No. 830,850.

To all whom it may concern:

Be it known that I, RAYMOND B. GILCHRIST, a resident of Newark, in the county of Essex and State of New Jersey, have invented certain new and useful Improvements in Article-Holders, of which the following is a full, clear, and exact description.

The invention relates to holders or dispensers for articles of merchandise, and more particularly to that type in which an elastic diaphragm or support is employed to sustain the articles, usually in a stack, so that the articles can be removed for use.

In devices for dispensing sanitary drinking cups or ice cream cones, it has heretofore been proposed to employ an elastic ring or diaphragm by which a stack of articles would be held and which permitted the lowermost article to be removed. In practice, these diaphragms are usually formed of rather soft rubber which at times becomes worn or dried out, so that they will be ineffective to properly hold the articles. In some dispensers, it is desirable to inter-changeably use diaphragms having holes of different diameters to dispense cups or cones of markedly different sizes. In order to be effective to hold articles, it is necessary that the outer margin of a soft rubber diaphragm be securely held or fixed and in devices heretofore used, the diaphragm has been clamped between rings or ring-like parts, one of which was a part of the case and the other of which had to be separated from the case in order to release the diaphragm for removal or replacement, and these parts were usually secured together by screws and nuts. In these prior devices, replacement of the diaphragm by an ordinary user was difficult, because, in many instances, the screws were difficult of access. Furthermore, if the user failed to firmly secure all portions of the outer edge of the diaphragm, it would not be effective to hold the articles.

One object of the invention is to provide an improved dispenser or holder in which the diaphragm may be readily removed and replaced by the ordinary user and which, when placed in position in the receptacle, will insure its effectiveness to hold the articles of the size or sizes for which the diaphragms are intended. This object is attained by providing a metallic binding at the outer edge of the diaphragm which can be readily placed into and out of operative

position and held there by a simple holding device. By employing this metallic binding, which in effect, becomes a rigid marginal part of the diaphragm and which is removable therewith, no skill upon the part of the ordinary user is necessary to place the diaphragm in the holder or to remove it therefrom, and the efficiency of the diaphragm in operation is insured because the securing of all portions of the margin of the rubber diaphragm is not dependent upon attachment by the user.

The invention further designs to provide an improved article dispenser or holder of this type which may be readily adapted for articles of different sizes by providing a number of diaphragms, which are constructed so that they may be readily placed in position in the holder by the ordinary user of these devices.

Lastly, the invention designs to provide an improved article holder which is simple in construction and efficient in operation.

In the drawings: Figure 1 is a vertical section of a dispenser embodying the invention. Fig. 2 is a perspective of the improved diaphragm with its metallic binding. Fig. 3 is a section of the same. Fig. 4 is a section showing the manner of uniting the diaphragm and its binding. Fig. 5 is a vertical section taken on line 5—5 of Fig. 1, the diaphragm being removed. Fig. 6 is a horizontal section taken on line 6—6 of Fig. 1. Fig. 7 is a detail of one of the grooved nuts for holding the binding of the diaphragm.

The dispenser comprises a base 10 to which is connected a clamp 11 whereby the device may be secured to a table or counter. A shell 12, provided with a hinged front door 14, is secured upon the base 10 by rods 15 which pass through a ring 16 on top of the shell, and the base 10, being secured to clamp the shell between said ring and the base, by nuts 17. Shell 12, base 10 and ring 16 form a case for inclosing the lowermost article of the stack, and from which the articles can be removed through door 14, which is held normally closed by a spring 14'.

A cylindrical magazine 18 of glass is mounted on top of ring 16, being secured between said ring and a cap-ring 19, by rods 20 which pass through rings 19 and 16 and are secured to clamp the case 18 by nuts 21, which engage the underside of ring 16. A rubber gasket 22 is placed between ring 19 and

and the upper end of magazine 18, and a gasket 24 is placed between the top of the ring 16 and the lower end of case 18 to provide dust-proof joints. A cover 25 is hinged to swing horizontally on ring 19, so that articles may be dropped into the magazine.

The lowermost article of the stack is held by a rubber diaphragm 27 which has a central opening 28 therein through which the lowermost article of the stack can be manually removed. This diaphragm has affixed thereto, a metallic binding 29 which holds the outer edge of the diaphragm against contraction, so that the central portion of the diaphragm will sufficiently resist expansion to inherently hold the articles, it being desirable to use a diaphragm of soft rubber so that articles such as ice cream cones will not be disintegrated when forced through the diaphragm. This metallic binding for the rubber consists of two rings 30 and 31. These rings are preferably formed of sheet metal and the former is provided with an annular groove 32 and ring 31 is formed with a corresponding annular rib 33 adapted to pass into groove 32 and to flex the diaphragm accordingly and firmly hold the outer edge thereof against inward movement. Ring 31 is held against one face of the diaphragm by a flange 33 on ring 30 which is tightly spun or pressed around the edge of and against the outer face of ring 31 so that the outer margin of the diaphragm will be securely held between these rings and so that they will form a substantially rigid metallic binding for the diaphragm, which is rigidly secured thereto, and is removable only with the diaphragm. The diaphragm and its binding form a holder for the articles.

The nuts 21 on the two rear rods 20 are provided with grooves 35 which are adapted to receive the edge of the metallic binding of the diaphragm and support the rear portion of the holder. The front of the holder is supported by a nut 36 on the lower end of the front rod 20. To facilitate placement of the holder in operative position, the margin of its binding is provided with a notch 37, which is adapted to clear the nut 36 so that the diaphragm may be tilted to put its rear portion into grooves 35 of nuts 21 when the notch 37 is aligned with, and below nut 36, and then the front of the holder may be raised into horizontal position. Then rotation of the holder will cause its binding at the front of the diaphragm to rest upon nut 36. If desired, the nut 36 may then be tightened to clamp the holder against the nut 21 on the front rod 20. Obviously, by reverse manipulation the holder may be quickly removed through the door 14.

It will thus be seen that the invention exemplifies a dispenser which is provided with a removable article holder which has a bind-

ing or marginal retaining means affixed to and removable with the diaphragm so that it is not necessary to manipulate devices for clamping the rubber diaphragm in place in removing or replacing the rubber diaphragm. Resultantly, the ordinary user may readily replace a defective diaphragm or place any one of a number of diaphragms having different sized openings in operative position and this is made possible by providing a diaphragm which has affixed thereto marginal retaining means or rings in lieu of being held in place by a retaining ring which must be removed from the receptacle before the diaphragm will be released for separate removal and requires the rubber diaphragm to be separately handled in placing it into or out of operative position. Furthermore, by employing a binding consisting of rings which may be pressed or spun into position to secure the margin of the diaphragm therebetween, the device may be produced at a low cost. By employing a rotatable binding ring fixed to the diaphragm, simple retaining means may be used therefor and it is not necessary to manipulate any nuts or retaining devices at the rear of the case.

The invention is not to be understood as restricted to the details set forth, since these may be modified within the scope of the appended claims without departing from the spirit and scope of the invention.

Having thus described the invention, what I claim as new and desire to secure by Letters Patent, is:

1. In dispensing apparatus for articles, the combination of an article holding device comprising an elastic diaphragm having an opening therein through which the articles can be removed and a metallic binding ring affixed to and extending completely around the margin of the diaphragm and a support by which the ring is removably sustained, the entire holding device being removable as a unit from the support.

2. In dispensing apparatus for articles, the combination of an article-holding device comprising an elastic diaphragm having an opening therein through which the articles can be removed, a metallic marginal binding-ring inseparably connected to the diaphragm and extending completely around it, and a support by which the ring is removably sustained, the entire holding device being removable as a unit from the support.

3. In dispensing apparatus for articles, the combination of a holding device comprising an elastic diaphragm having an opening therein through which articles may be removed and marginal metallic binding for the diaphragm consisting of two rings extending completely around the diaphragm and fixedly secured together with the mar-

- gin of the diaphragm therebetween, and a support on which the binding is removably held, the entire holding device being removable as a unit from the support.
5. Dispensing apparatus comprising the combination of a case, a diaphragm in the case and having an opening through which articles may be removed, a metallic binding for the diaphragm consisting of two rings 10 fixedly secured together with the margin of the diaphragm therebetween so as to retain the diaphragm when it is removed from the case, and means for removably holding the binding in the case.
15. Dispensing apparatus comprising the combination of an elastic diaphragm having a hole therein, and for removably holding the articles, and a metallic binding for the margin of the diaphragm consisting of 20 two rings on opposite sides of the margin of the diaphragm, the rings having an interfitting groove and rib respectively, and means fixedly securing the rings together with the diaphragm therebetween.
25. Dispensing apparatus comprising the combination of an elastic diaphragm for removably holding the articles, and a metallic binding for the margin of the diaphragm consisting of two rings on opposite sides of 30 the margin of the diaphragm, one of the rings extending around and over the edge of the other to secure the rings together with the diaphragm therebetween.
35. Dispensing apparatus comprising the combination of a case, an elastic diaphragm for holding the articles and having an open-

ing therein through which the articles may be withdrawn, a metallic binding secured to the diaphragm, and means for rotatably sustaining the binding in the case.

40. Dispensing apparatus comprising the combination of a case, an elastic diaphragm for holding the articles and having an opening therein through which the articles may be withdrawn, a metallic binding secured 45 to the diaphragm, and means in the case for removably and rotatably sustaining the binding.

45. Dispensing apparatus comprising the combination of a case, an elastic diaphragm 50 for holding the articles, having an opening therein through which the articles may be withdrawn, a metallic binding secured to the diaphragm, and means for rotatably sustaining the binding, the latter having a 55 notch therein to facilitate placement on the supporting means.

55. Dispensing apparatus comprising the combination of a case, an elastic diaphragm for holding the articles and having an opening therein through which the articles may be withdrawn, a metallic binding secured to the diaphragm, and means in the case for removably sustaining the binding, the binding and diaphragm being removable 60 from the case without displacing the binding supporting-means.
